UNITED STATES PATENT OFFICE.

ALBERT W. PEARSALL, OF LOWELL, MASSACHUSETTS, ASSIGNOR TO LAMSON COMPANY, OF NEWARK, NEW JERSEY, A CORPORATION OF NEW JERSEY.

PNEUMATIC-DESPATCH-TUBE APPARATUS.

1,122,629.

Specification of Letters Patent. Patented Dec. 29, 1914.

Application filed November 29, 1907. Serial No. 404,317.

To all whom it may concern:

Be it known that I, ALBERT W. PEARSALL, of Lowell, in the county of Middlesex and State of Massachusetts, have invented certain new and useful Improvements in Pneumatic-Despatch-Tube Apparatus, of which the following is a specification.

My invention relates to improvements in pneumatic despatch tube apparatus and its object is to control and limit the use of the power to the interval necessary for the proper transmission and delivery of the carriers. This object is accomplished by using a blower or pump connected with one end of a system of transmission tubes and driven by a motor adapted to be started into operation to establish a current of air for driving the carriers, by means located at each despatching station along the line, and a timing device which is adapted to stop the carrier driving operation of the motor after a sufficient interval has elapsed for the proper transmission of the carriers.

In the accompanying drawings, which illustrate the preferred form of system embodying my invention, in which an electric motor is used and controlled by switches at the despatching stations and an automatic circuit breaker operated by the timing device, Figure 1 is a diagrammatic view of a system showing the parts in normal or non-operating position. Fig. 2 is an enlarged sectional elevation of the automatic switch or circuit breaker in normal or non-operating position. Fig. 3 is a similar view to Fig. 2 showing the parts in operating position.

Like letters of reference refer to like parts throughout the several views.

Referring to Fig. 1, A and B represent two stations connected by the tube C for the transmission of carriers from station to station A to station B and by the tube D for the return of carriers from the station B to station A. The tube C has an open end or bell-mouth located at station A and connects at station B with the ordinary upward discharge terminal B' controlled by the usual delivery valve B². The tube D connects the terminal B' with the terminal D² located at station A which terminal D² is controlled by the usual valve D². D' is a despatching inlet for inserting carriers into the tube D for transmission and E and G are vacuum tubes

connecting the terminal D² with the blower or pump P there being interposed between said tubes the automatic timing mechanism F. M is an electric motor adapted to drive the blower P through a belt m. a and b are switches located at stations A and B respectively and are in circuit with and adapted through an electro-magnet R and swing-switch Y to close the circuit through motor M and start said motor and blower P into operation.

The timing mechanism (Figs. 2 and 3) consists of the casting F', the lower part of which comprises a cylinder F² in which is mounted the piston F³ fixed to the piston rod F⁴. The upper part of said casting comprises two chambers E' and G' connected respectively with the tubes E and G, said chambers adapted to be placed into communication through an opening F⁶ normally closed by a valve F⁶ secured to the upper end of the piston rod F⁴. The vacuum chamber G' is in continuous communication with the chamber F⁷ through port G² in the cylinder F² above the piston F³, and the chamber F⁸ is normally in communication through a port F¹⁰, normally closed to the atmosphere by a valve F¹¹, and a by-pass F⁹ restricted by a timing valve F¹² and held in adjustment by a set screw F¹³, with said vacuum chamber G'. This by-pass F⁹ normally balances the vacuum on the upper and lower sides of the piston F³ causing said piston to hold the valve F⁶ closed by gravity as shown in Fig. 2. The valve F¹¹ is mounted on one end of a bell-crank lever F¹⁴ pivoted at F¹⁵ and normally held closed by a spring F¹⁶.

An armature F¹⁷ fixed to the other end of said lever F¹⁴ is adapted to be operated by a magnet F¹⁸ to open the valve F¹¹ and admit air through the port F¹⁰ to the chamber F⁸ beneath the piston F³. This magnet is in circuit with a battery X and the normally open switches a and b located at stations A and B respectively and also with the electro-magnet R.

f is a normally open automatic switch mounted on the top of the casing F' and adapted to control a shunt circuit through battery X and the magnet R.

f³ is a rod secured to the valve F⁶ and projecting through the upper part of the casing F' and carrying fixed to its outer end a collar f⁴. In the normal or closed position of

the valve F^8 (Fig. 2) the collar f^4 holds the contact f^2 of switch f away from contact f' leaving the switch f and shunt circuit open. 8 is the ordinary main switch or cut-out.

5 The operation of the system is as follows:—To despatch a carrier from station A to station B the operator closes the switch a and inserts the carrier into the bell-mouth C'. The closing of switch a energizes the magnet R attracting the armature Y' and throwing the contact Y^2 of swing switch Y against the contact Z closing the circuit through motor M as follows,—from line wire L through main switch s , wire I, contacts Y^2 and Z, and wire 2 through motor M, thence through wire 3 and switch s to line wire L'. The motor M now started drives the blower P creating a vacuum in the tube G and chamber G'. Simultaneously with the closing of the switch a the magnet F^{18} is energized opening the valve F^{11} admitting air to the chamber F^8 against the vacuum in chambers G' and F' and thus moving the piston F^8 and valve F^8 upward creating a current of air through chamber E' and tubes E, D and C in the direction indicated by arrows (Fig. 3) and transmitting the carrier toward station B. The circuit through switch a is as follows,—from battery X through wire a' , magnet F^{18} , wire a^2 , switch a , wires a^3 and r' and magnet R, thence back to battery X through wire r' . In the meantime the opening of valve F^8 moves the collar f^4 upward releasing contact f^2 closing the switch f and a shunt circuit from battery X through wires a' , f^{10} , switch f , wire f^{11} , magnet R and wire r^2 back to battery X. The closing of this circuit holds the magnet R and switch Y closed keeping the motor M in operation. After the carrier has been despatched the operator releases and opens the switch a deenergizing the magnet F^{18} allowing the valve F^{11} to close shutting off the admission of air to chamber F^8 . The air under the piston F^8 is now gradually exhausted through the by-pass F^9 being timed by the adjustment of valve F^{12} allowing the piston F^8 and valve F^8 to drop by gravity so that by the time the carrier has delivered at station B the valve F^8 has entirely closed shutting off the flow of air. The valve F^8 having closed the collar f^4 has engaged and separated contact f^2 from contact f' opening switch f and breaking the shunt circuit deenergizing the magnet R allowing the switch Y to open breaking the motor circuit and stopping the motor.

In despatching a carrier from station B to station A the carrier is inserted through the inlet D' into tube D and the switch b closed. The switch b being in multiple with switch a the motor is started, the carrier transmitted and the motor stopped in a manner identical with that heretofore described.

It will be seen that any number of despatching stations and switches may be used on a line and that any number of carriers may be sent from the same or separate despatching stations without waiting for the delivery of carriers, the timing mechanism being re-set at each operation of a switch at a despatching station by the closing of a circuit through magnet F^{18} , opening valve F^{11} and raising piston F^8 by the admission of air below the piston, so that the full operation of the motor for the transmission of each successive carrier is thus secured.

Having thus described my invention and set forth a construction embodying the same, what I claim as new and desire to secure by Letters Patent of the United States, is:

1. In a pneumatic despatch tube apparatus, a tube for the transmission of carriers, sending stations for inserting carriers into said tube for transmission, a blower or pump, an electric motor adapted to drive said blower or pump, means connecting said transmission tube with said blower or pump, a valve normally closing said connecting means, means located at said sending stations adapted to control the circuit of said motor to cut said motor and blower into operation to open said valve and create a current of air in said tube for transmitting carriers, means for timing the closure of said valve to the interval necessary for the transmission and delivery of said carriers, and a switch adapted to be operated by said valve to control the current of said motor to maintain said motor and blower in such operation for the transmission of said carriers and to cut out of such operation said motor and blower independently of the travel of the carriers.

2. In a pneumatic despatch tube apparatus, a tube for the transmission of carriers, sending stations for inserting carriers into said tube for transmission, a blower or pump, an electric motor adapted to drive said blower or pump, means connecting said transmission tube with said blower or pump, a valve normally closing said connecting means, a magnet controlling the circuit of said motor, a normally open switch located at each sending station in circuit with said magnet and adapted to operate said magnet to cut said motor and blower into operation to open said valve and create a current of air in said tube for transmitting carriers, means for timing the closure of said valve to the interval necessary for the transmission and delivery of said carriers, a shunt circuit through said magnet and a switch adapted to be operated by said valve to operate said magnet to maintain said motor in such operation for the transmission of

said carriers and to cut out of such operation said motor independently of the travel of the carriers.

3. In a pneumatic despatch tube apparatus, a tube for the transmission of carriers, air displacing means connected with said tube and adapted to be operated to create a current of air in said tube effective for carrier propulsion, a motor adapted to drive said air displacing means, means for controlling said motor to render it operative to create said current of air, timing means operable by power and acting to allow said motor to operate in manner aforesaid, 15 said, for an interval determined by said timing means and then to automatically limit such operation of said motor, and connections whereby power for actuating said timing means is obtained substantially immediately from said air displacing means.

4. In a pneumatic despatch tube apparatus, a tube for the transmission of carriers, air displacing means connected with said tube and adapted to be operated to create a current of air in said tube effective for carrier propulsion, a motor adapted to drive said air displacing means, means for controlling said motor to render it operative to create said current of air, timing means operable by power and acting to allow said motor to operate in manner aforesaid, for an interval determined by said timing means and then to automatically limit such operation of said motor, connections whereby power for actuating said timing means is obtained substantially immediately from said air displacing means, said timing means being normally inoperable until said motor 40 has been rendered operative, and means for starting said motor preparatory to actuating said timing means.

5. In a pneumatic despatch tube apparatus, a tube for the transmission of carriers, air displacing means connected with said tube and adapted to be operated to create a current of air in said tube effective for carrier propulsion, a motor adapted to drive said air displacing means, means for controlling said motor to render it operative to create said current of air, and a timing device operable by power initially obtained from said motor and acting to allow said motor to operate in manner aforesaid, for an interval determined by said timing means and then to automatically limit such operation of said motor, said apparatus including connections for transmitting power, initially obtained from said motor, to said timing device.

6. In a pneumatic despatch tube apparatus, a tube for the transmission of carriers, air displacing means connected with said tube and adapted to be operated to create a current of air in said tube effective for

carrier propulsion, a motor adapted to drive said air displacing means, means for controlling said motor to render it operative to create said current of air, said motor controlling means including a timing element 70 acting to allow said motor to operate in manner aforesaid, for an interval determined by said element and then to limit such operation of said motor, said apparatus including connections for insuring effective 75 operation of said motor before said element becomes operative to time said motor operation.

7. In a pneumatic despatch tube apparatus, a tube for the transmission of carriers, 80 said tube having a receiving terminal, a mechanical source of power normally inoperative for carrier transmission purposes, connections between said mechanical source of power and said tube adapted to coöperate 85 with said source and establish a current of air in said tube effective for carrier propulsion, a timing element, acting when operative, to allow power to be supplied by said source for carrier transmission purposes for 90 an interval determined by said element and then to automatically limit such supply of power, said timing element also being actuatable by power supplied by said source, and means for first rendering said power source 95 operative and thereafter causing actuation of said timing element, said means including a controlling part disposed substantially at one of said terminals, said timing element adapted to re-time for successive actuations 100 of said last mentioned means.

8. In a pneumatic despatch tube apparatus, a tube for the transmission of carriers, air displacing means adapted to create a current of air in said tube effective for 105 carrier propulsion, connections between said means and said tube, a valve for controlling the flow of air through said connections, timing means for controlling said valve, a motor for driving said air displacing means, 110 and instrumentalities between said timing means and said motor for controlling the latter.

9. In a pneumatic despatch tube apparatus, a tube for the transmission of carriers, air displacing means adapted to create a current of air in said tube effective for carrier propulsion, connections between said means and said tube, a valve for controlling the flow of air through said connections, 115 timing means for controlling said valve, a motor for driving said air displacing means, instrumentalities between said timing means and said motor for controlling the latter, connections between said air displacing 120 means and said timing means for actuating the latter, and means for controlling such actuation of said timing means.

10. In a pneumatic despatch tube apparatus, a tube for the transmission of car- 120

- riers, a mechanical source of power normally inoperative for carrier transmission purposes, connections between said source of power and said tube adapted to coöperate 5 with said source to establish a current of air in said tube effective for carrier propulsion, a timing element, acting when operative, to allow power to be supplied by said source for carrier transmission purposes for 10 an interval determined by said element and then to automatically limit such supply of power, and means for first rendering said mechanical source of power operative and for thereafter actuating said timing element.
11. In a pneumatic despatch tube apparatus, a tube for the transmission of carriers, said tube having a receiving terminal, a mechanical source of power normally inoperative for carrier transmission purposes, 15 connections between said source of power and said tube adapted to coöperate with said source and establish a current of air in said tube effective for carrier propulsion, a timing element, acting when operative, to 20 allow power to be supplied by said source for carrier transmission purposes for an interval determined by said element and then to automatically limit such supply of mechanical power, said timing element also 25 being actuatable by power supplied by said source, and means for first rendering said power source operative and thereafter causing actuation of said timing element, said 30 means including a controlling part disposed substantially at said receiving terminal, said timing element adapted to re-time for successive actuations of said last mentioned means.
12. In a pneumatic despatch tube apparatus, a receiving station, a tube connected thereto for the transmission of carriers, and air displacing means connected with said tube and adapted to be operated to create a current of air in said tube effective for carrier 45 propulsion, a motor adapted to drive said air displacing means, means for controlling said motor to render it operative to create said current of air, fluid pressure operated timing means acting to allow the 50 motor to thus operate for an interval determined by the timing means and then to automatically limit such operation of said motor, a valve for controlling the fluid which operates said timing means, and 55 means for controlling said valve from said receiving station.
13. In a pneumatic despatch tube apparatus, a receiving station, a tube connected thereto for the transmission of carriers, and air displacing means connected with said tube and adapted to be operated to create a current of air in said tube effective for carrier propulsion, a motor adapted to drive said air displacing means, means for controlling said motor to render it operative to 60 create said current of air, timing means acting to allow the motor to thus operate for an interval determined by the timing means and then to automatically limit such operation of said motor, said system having 65 provisions for insuring that the timed interval shall start to run only after pressure conditions, substantially at said air displacing means, are such as to permit of the transmission of a carrier from said station 70 properly through said tube to a determined point therein.
14. In a pneumatic despatch tube apparatus, a tube for the transmission of carriers between stations, a pump for creating 80 a carrier propelling current of air through said tube, a motor to drive said pump, a branched electric circuit having a circuit making device in one branch thereof to control the energization of a part at least of 85 said motor, said circuit having in a second branch thereof contacts which control the flow of current through said second branch, a timing mechanism to control one at least of said contacts, an electro-magnetic device 90 in said first mentioned branch to control the starting of said timing mechanism to time said motor, and an electro-magnetically operated device controlled by both of said branches and in turn controlling the running of said motor, said last mentioned device being normally operative to drive said motor, and thereby said pump to create said current of air only so long as said contacts in said second branch are out of their normal relationship and said timing mechanism determining the time during which said contacts are thus operatively disposed to drive said motor.
- In testimony whereof I have signed my 105 name to this specification in the presence of two subscribing witnesses, this twenty-first day of November, A. D. 1907.
- ALBERT W. PEARSALL.
